John A. Redfield

INVENTOR.

UNITED STATES PATENT OFFICE.

JOHN A. REDFIELD, OF HOUSTON, TEXAS.

MOUTHPIECE FOR CLARINETS.

1,375,467.

Specification of Letters Patent. Patented Apr. 19, 1921.

Application filed August 21, 1920. Serial No. 405,142.

To all whom it may concern:

Be it known that I, JOHN A. REDFIELD, a citizen of the United States, residing at Houston, in the county of Harris and State of Texas, have invented a new and useful Improvement in Mouthpieces for Clarinets, of which the following is a specification.

My invention relates to improvements in the clarinet mouthpiece; and the objects of my improvement are, first, to secure a better tone for the clarinet; second, to render the clarinet more easily blown; and, third, to make possible greater variations of loudness and softness in tone.

I attain these objects in a mouthpiece illustrated in the accompanying drawing in which—

Figure 1 is a view of the bottom of the mouthpiece;

Fig. 2 is a view of the side of the mouthpiece;

Fig. 3 is a view of the top of the mouthpiece;

Fig. 4 is a view of the front end of the mouthpiece;

Fig. 5 is a view of the rear end of the mouthpiece.

The dotted straight lines in Figs. 1, 2 and 3 show the air chamber within the mouthpiece to be of cylindrical form. Figs. 4 and 5 also show the cylindrical character of the air chamber. The ellipses of Figs. 1 and 3 show the intersection of the cylindrical air chamber with the table upon which the reed rests. This table, except for a slight curvature at the tip of the mouthpiece constituting the "lay" of the mouthpiece, is a plane.

The clarinet, theoretically, is a cylindrical column of air set in motion by a single beating reed, *i. e.* a reed that alternately closes and opens the orifice between the reed and

the air column. Other mouthpieces, instead of preserving the cylindrical character of the air column throughout the length of the mouthpiece, reduce the area of the cross-section of the air column and allow the cross-section to assume other shapes than the circle. In consequence the free passage of the air inside the mouthpiece toward and from the reed is interfered with and hindered. My mouthpiece, being cylindrical and of the same caliber as that part of the clarinet to which it joins, permits the freest possible passage of the air within the mouthpiece to and from the reed. As a result three improvements are secured: (a) the tone of the instrument is bigger, fuller, rounder and mellower, and conforms more closely to those tones considered characteristic and peculiar to the clarinet; (b) the instrument blows more easily; and, (c) it is possible to secure greater variations of loudness and softness in tone.

Having thus described my invention and its advantages, I claim:

1. A clarinet mouthpiece having a cylindrical bore the upper base of the mouthpiece being a plane oblique to the axis of the bore which upper base serves as a table for the reed to rest upon.

2. A clarinet mouthpiece having a bore approximately cylindrical the upper base of the mouthpiece being a plane oblique to the axis of the bore which upper base serves as a table for the reed to rest upon.

In testimony whereof I have signed this specification in the presence of two subscribing witnesses this eighteenth day of August, 1920.

JOHN A. REDFIELD.
